UNITED STATES PATENT OFFICE.

ADOLPH J. P. BERTSCHY, OF PLATTSMOUTH, NEBRASKA, ASSIGNOR TO DAVID O. BARNELL, OF OMAHA, NEBRASKA.

AUXILIARY CHARGE-FORMING MEANS FOR INTERNAL-COMBUSTION ENGINES.

Application filed May 9, 1925. Serial No. 29,135.

My invention relates to charge-forming means for internal-combustion engines of the class commonly employed in motor vehicles, in which the engine-cylinders are 5 cooled by liquid which is circulated through the cylinder-jackets and a radiator. It is the object of my invention to provide for such engines, as an auxiliary to the usual carburetor, a charge-forming device for 10 utilizing the combustible vapors formed in the crank-case of the engine and escaping to the crank-case from the cylinders, and the moisture, or vapors from the cooling-liquid, which escape from the radiator. A further 15 object of my invention is to provide auxiliary charge-forming means of the above type which may be conveniently applied to the engines of motor vehicles, with a minimum alteration of the customary equipment of such engines, and requiring a minimum of adaptative variations in the auxiliary charge-forming device itself to enable 20 its application to any motor vehicle now commercially produced. A further object 25 of my invention is to provide an auxiliary charge-forming device which, when properly installed and adjusted, will not alter or disturb the normal functioning of the regular carburetor, nor require any adjustment 30 of the usual charge-controlling means except the reduction of the minimum throttle-opening which determines the idling-speed of the engine. A further object of my invention is to provide auxiliary charge-forming means 35 which conserve the vapors from the crank-case and radiator, and also prevent admission or retention in the crankcase of any constituents tending to dilute or impair the lubricating efficiency of the crank-case oil. 40 A further object of my invention is to provide an auxiliary charge-forming device of the general character above set forth, having automatically operating suction-controlling means adapted to limit the flow of vapors through the same to the intake-manifold, and whereby increase of the engine-speed and the resulting increase of suction at the intake-manifold, will effect an increase of the frictional resistance to flow of 45 the vapors through the auxiliary device, and thus prevent excessive intake of the auxiliary vapors. A further object of my invention is to provide automatic suction-controlling means of the character above 50 set forth, so constructed and arranged as to become inoperative when the engine is cooled below a temperature at which there is an appreciable evolution of vapors from the radiator, and to resume operation when the engine becomes heated to a temperature 60 at which there is evolution of such vapors in utilizable quantity.

In the accompanying drawings Fig. 1 is a side view of a device embodying my invention, and showing the parts of the engine 65 with which the same is connected, Fig. 2 is a detail vertical section of the suction-controlling valves, Fig. 3 is a detail vertical section of the connection to the overflow-pipe of the radiator, Fig. 4 is a vertical 70 section on the line 4-4 of Fig. 2, showing a variation of the connections with the intake-manifold, and Fig. 5 is a detail horizontal section on the line 5-5 of Fig. 2.

In carrying out my invention I provide, 75 primarily, means for collecting the vapors from the radiator and from the engine crank-case combining said vapors, and delivering the same into the intake-manifold of the engine. The connection to the crank-case should be at the upper portion thereof, whereby there will be the least probability of withdrawing therefrom any liquid particles of the lubricating oil which is splashed within the crank-case when the engine is 80 running. Usually the highest point at which the connection may be made with the crank-case is at one side of the breather-tube, and, accordingly, there is indicated in Fig. 1 the portion of the crank-case 6 with which 85 the breather-tube 7 is connected. In the side of said tube 7 a hole is drilled and tapped for receiving a nipple 8, said nipple having at the outer end thereof the nut 9 of a compression-coupling with which the metal tube 90 10 is connected and from which said tube extends to one inlet of the vapor-combining and controlling unit.

In the usual construction of motor vehicles driven by liquid-cooled internal-combustion engines, there is a radiator 11 having at the upper portion thereof a chamber from which an overflow tube 12 extends down alongside the cellular or tubular portion of the radiator body, said tube discharging 100 any excess of the cooling-liquid and any vapor that may be given off from the cooling-liquid as the same becomes heated during the running of the engine. In order to effectively collect the vapor discharged from 110

- the tube 12, and at the same time to allow the free discharge of any liquid that may overflow from the radiator, I dispose about the lower end of said tube a pipe-T 13 of which the internal diameter is approximately twice the outer diameter of the tube, attaching the T to the tube by any suitable means, such as a drop of solder 14 flowed into the space about the tube at the upper 10 end of the T, the T being so positioned that the lower end of the tube terminates substantially at the lower edge of the lateral opening of the T, as best shown in Fig. 3. Into said lateral opening of the T 13 is screwed 15 a nipple 15 having at its end the nut 16 of a compression-coupling for connection with the tube 17 which is extended to the second inlet of the vapor-combining and controlling unit.
- 20 The outlet from the vapor-combining and controlling unit is connected with the intake-manifold 18 of the engine, and is usually made at the opening in said manifold provided for connection with the suction-tube 19 from the vacuum-tank 20 by which fuel is supplied to the carburetor. When the manifold is not provided with the opening for connection with the vacuum-tank suction-tube, I form an equivalent opening by 25 drilling and tapping a hole in the side of the manifold at a point intermediate the carburetor connection and the Y or division of the manifold from which its separate branches extend to the engine-cylinders. In 30 the illustrated structure it is assumed that the assemblage includes the vacuum-tank 20, and in such case the usual direct connection of the suction-tube 19 to the manifold is displaced by the connection thereto from the vapor-combining and controlling 35 unit, the latter connection having a branch to which the tube 19 is attached. The branch last referred to is the lateral opening of a T 21 to which said tube 19 is connected by the usual nipple 22 and nut 23 of a compression-coupling. The T 21 is connected with the manifold by a pipe-elbow 24 in the arrangement shown in Figs. 1 and 2, and by a pipe-nipple 25 in the 40 arrangement shown in Fig. 4. In each case the remaining branch of the T 21 is connected by the pipe-nipple 26 with the outlet of the vapor-combining and controlling unit. In the case of an engine not provided 45 with the vacuum-tank 20, the T 21 is omitted and the nipple 26 is connected with the manifold, either directly or by suitable pipe-fittings, as may be desired.
- 50 The outlet to which the nipple 26 is connected is formed at one side of a valve-body 27 having a seat formed at the inner end of the opening leading to said nipple. The valve 28 for engagement with said seat is formed at the end of a threaded stem 29 which extends through the side of the body 55 opposite the nipple 26, the protruding end of said stem having a knurled head 30, and a knurled lock-nut 31 being disposed upon the stem for retaining the same in adjusted positions. The valve 28 intersects a transverse passage through the body 27, said passage traversing the oppositely extending externally threaded nipples 32, which are formed integrally with the body 27 and upon which are screwed the bodies 33 of the automatic suction-controlling valves. Said valve-bodies 33 are of identical form, being merely disposed in right and left relation to the body 27. At the lower end of each body 33 is a threaded opening into which is screwed the upper branch of a T-shaped valve-body 34 having a seat formed at the lower end of the passage through said upper branch, a valve 35 being arranged to engage said seat, said valve 35 being formed at the inner end of a threaded stem 36 which extends through the lower branch of the body 34, the lower end of said stem having a knurled head 37, and a knurled lock-nut 38 being disposed upon the threaded stem for retaining the same in adjusted positions. The lateral branches of the bodies 34 are threaded externally and provided with nuts 39 to form compression-couplings for connection with the tubes 10 and 17. The valves 35 are employed for separately regulating the intake of vapors from the crank-case and radiator, supplied respectively through said tubes 10 and 17, and the valve 35 serves to regulate or to shut off, if desired, the admission of the combined vapors from the control-unit to the manifold. The upper ends of the bodies 33 are threaded internally to receive the plugs or heads 40 which close the upper ends of the valve-chambers 41. The main portion of each chamber 41 is trunco-conical in form, the larger end being uppermost, and the lower end merging into a short cylindrical portion which adjoins the seat 42. Said seat has a central opening in which the lower portion of the valve-stem 43 is guided, and a plurality of peripheral openings which communicate with the inlet passage from the respective regulating-valve 34. The upper portion of the valve-stem 43 extends slidably through a central opening in the plug or head 40, and said head has a portion 44 which extends down into the chamber 41 to form a stop for limiting upward movement of the valve 45. Said valve 45 is formed by a thin disk or circular plate secured to or made integral with the stem 43, the diameter thereof being such that the disk is slidable within the lower cylindrical portion of the chamber 41, and adapted to engage the seat 42 to cover and shut off the openings through said seat.
- 55 In the installation of the described devices upon the engine of a motor vehicle,

- the valve-bodies 33 are disposed vertically, but the positions of the other parts are variable as may be most convenient for the extension of the tubes 10, 17 and 19 between the parts connected thereby. The valve-body 27 may be rotated about the horizontal axis of the nipples 32, so that the outlet connected with the nipple 26 extends vertically as in Figs. 1 and 2, horizontally as in Fig. 10, 4, or at any intermediate angle. Similarly, each of the bodies 34 may be rotated about the axis of its vertical branches, so that its lateral branch extends in the direction which is best suited for connection with the 15 tubes 10 or 17. The T 21 may also be rotated so that its lateral branch extends in that direction which is most convenient for connection with the tube 19. The tubes 10, 17 and 19 may be readily bent so as to pass 20 around parts of the engine or other structure which may extend between the parts connected by said tubes. It will thus be seen that the device is universally applicable to the engines of all standard motor vehicles, with a minimum of adaptative alterations 25 of parts, and without change of the principal structural elements.
- It will be noted that the outlet from the vapor combining and controlling device is 30 connected with the manifold at a point between the carburetor intake and the cylinders, and, as the engine throttle is usually associated with the carburetor, the intake of vapors from the auxiliary device will not 35 be controlled by the throttle. When the device is installed in connection with a vacuum-tank, as shown, the area of the passage through the parts 21 and 24 or 25, should be substantially equal to the combined area of 40 the passage through the tube 19 and the opening through the seat of the valve 28, so that should the latter valve be fully opened the suction to the vacuum-tank will not be so lowered as to be ineffective.
- 45 After the device has been installed, as hereinbefore described, testing and adjustment thereof for operation may be effected as follows: The valve 28 and both of the valves 35 are first closed, and the engine 50 started and operated for such time as may be required to bring the same to a normal or average working temperature. The valve 28 is then opened slightly, and the operation of one of the valves 45 tested by slightly 55 opening the respective valve 35. The suction in the chamber 41 should lift the valve 45, which is shown by the raising of the protruding end of the valve-stem 43, and the force of the suction upon said valve 45 may 60 be ascertained by pressing down upon its stem. The first-opened valve 35 is then closed, and the other valve 45 tested in like manner by opening the second valve 35. After the operation of the valves 45 has been 65 tested, the adjustment of the device may be made. First, both of the valves 35 are closed to stop all supply of vapors from the crank-case and radiator, and the throttle is set at a position such that the engine will run slowly, but not at a minimum speed. 70 Then the valve 35 of the crank-case connection is slowly opened. Usually upon the opening of said valve the engine-speed will be slightly reduced, due to the enriching of the combustible mixture by the addition of 75 the vapors drawn from the crank-case and added to the mixture supplied from the carburetor. The other valve 35, controlling the connection to the radiator, is then opened. As the tube 17 is open to atmosphere at the end thereof adjoining the radiator-overflow tube 12, a large proportion of air will be drawn through said tube, together with the vapors emitted from the tube 12. Said vapors will consist largely of 80 moisture or water-vapor, although in winter, when an alcoholic mixture is used as a non-freezing cooling-liquid, some of the emitted vapor will be combustible. The air drawn through the tube 17 causes a leaner mixture 85 to be supplied to the engine, so that the speed thereof will be increased, and will become greater than when the entire combustible charge was received from the carburetor. Tentative or trial adjustments of 90 the valves 35 and 28 may be continued until the engine-speed has been increased as much as possible without changing the position of the throttle, and the attainment of such speed will indicate a proper proportioning 95 of the charge-elements supplied through the tubes 10 and 17. Finally, the throttle is adjusted as to its minimum-opening or idling position, so that the desired idling-speed of 100 the engine will be attained, while the auxiliary charge is being supplied. Upon completion of the adjustments, the valve 28 and valves 35 are secured in adjusted position 105 by tightening down the lock-nuts 31 and 38, and the engine may then be operated in the 110 usual way by manual variation of the position of the throttle to secure the desired speed.
- When the device has been properly adjusted, as above set forth, the control of the auxiliary charge-elements at various engine-speeds is effected automatically by the valves 45, and it will be necessary to consider in detail the manner in which said valves perform this function. When said 115 valves 45 are engaged with the seats 42 and suction from the manifold causes a lowering of pressure in the valve-chambers 41, the pressure in the intake-passages below the valves will lift the same from their seats, as 120 the latter pressure will be substantially atmospheric until the valves assume an open position. Because of the sliding fit of the valve-disks in the lower cylindrical portions 125 of the chambers 41, there is no appreciable 130

opening formed about the disks until the same have been lifted into the conical portions of the valve-chambers. After the valves enter the upper or conical portions 5 of the chambers, the area of the annular passages about the disks becomes greater as the upward movement is continued. Upon the opening of the valves the suction from the chambers 41 is communicated to the intake 10 passages below the valves, and there is a corresponding lowering of pressure in said intake passages, to which the supply from atmosphere is limited by the adjusting-valves 35.

It will now be noted that as the upper 15 portions of the valve-stems 43 extend through the heads 40, the upper ends of said stems are constantly subject to atmospheric pressure, while the lower ends of the valve-stems are in the intake passages and are 20 thus subject to the reduced or sub-atmospheric pressure existing in said intake passages when the valves are open. In consequence of the facts noted, it is found that during the operation of the device the valves 25 45 tend to assume positions intermediate the seats 42 and the upper stops 44, such as indicated by dotted lines in Fig. 2, the exact positions being dependent upon the intensity of suction from the manifold and the 30 extent to which the intake passages are restricted by the adjusting-valves 35. It will be obvious that while the conditions remain constant each valve 45 will remain in balance at a position such that the restriction 35 or resistance offered to the flow of elastic fluids about its edges will result in a difference of pressures upon the upper and lower surfaces of the disk, equal to the weight of the valve plus the excess of atmospheric 40 pressure upon the upper end of the stem over the pressure in the intake passage at the lower end of the stem. It will be seen that, with a given suction in the chamber 41 above the valve-disk, if the valve is at an 45 elevation such that the opening about its edges enables the pressure in the intake passage to become reduced below the balancing-pressure, the valve will be constrained to move downwardly in the conical chamber, to 50 thereby reduce the area of the annular opening about its edges and increase the frictional resistance therat until the pressures are restored to the balancing-point. By 55 reason of the action above noted, it is observed in practice that when the speed of the engine exceeds a critical minimum, the valves begin a downward movement, which continues as the engine-speed increases. The valves thus offer a progressively increasing 60 resistance to the flow of elastic fluid past them, as the suction at the manifold is increased, and thus automatically limit the intake of the auxiliary charge-forming constituents through the tubes 10 and 17, so that for all speeds of the engine

the regular carburetor will continue to function in a normal manner, without requiring re-adjustment thereof, and without its operation being changed except that the volume of the charge delivered by it will be reduced 70 proportionally to the volume of the auxiliary charge supplied.

The automatic control-valves have a further purpose and function in the mechanism, resulting from the configuration of the upper surfaces thereof and their relation to the walls of the valve-chambers. The flat upper surfaces of the valve-disks do not conform with the streamline of the fluids which pass about the edges of the disks, and, consequently, there is an eddying of said fluids over the central portions of the disks. By reason thereof, it is found that after the device has been in operation for a time, there is a slight accumulation of liquid upon 80 the upper surfaces of the disks 45, said liquid being water on the valve which controls the intake of vapor from the radiator, and usually being lubricating oil on the valve which controls intake from the crank-case. 85 While the running of the engine is continued the accumulation of liquid on the upper surfaces of the valves is maintained by the eddy-currents, but when the engine is stopped the liquid spreads to the edges of 90 the disks and seeps into the joints between the disks and their seats 42. In winter, when the engine has been stopped for such a time that the temperature of the parts becomes reduced substantially to that of 100 the atmosphere, the water in the seat-joint and about the edges of the valve controlling the intake from the pipe 17, freezes and causes said valve to adhere to the seat. This valve is thereby rendered inoperative 105 until the engine has been started and run for such time that heat therefrom will commence to melt the film of ice upon the valve-seat. At extremely low temperatures, the film of lubricating oil 110 upon and around the seat of the other control-valve, will become so thick and adhesive as to retard opening of said valve, so that said valve may also become inoperative until the engine has been run for a short time; or 115 until excessive suction has been caused in the manifold by racing or extreme acceleration of the engine-speed. Now it is desirable that the last-mentioned valve become operative soon after the engine is started, 120 as there are combustible vapors present in the crank-case almost immediately upon the starting of the engine, and the delivery of said vapors to the intake manifold aids in the production of the richer charge which is 125 required when the engine is cold. The inhibition of opening of the other control-valve until such time as the engine has become thoroughly heated, also conforms closely with the desired conditions, because until 130

such temperature conditions have been attained the leaner mixture resulting from intake of air through the pipe 17 would be disadvantageous, and furthermore, there will be no appreciable production of vapor from the radiator until the cooling-liquid has been warmed to a temperature above the freezing-point of water. The valve becomes operative, therefore, at a time closely coincident with that at which it becomes desirable to supply a leaner charge, and when emission of vapor from the radiator commences.

The advantages, incident to the introduction of moisture or water-vapor as a constituent of the charge supplied to an internal-combustion engine, are well-known, and it has often been demonstrated that the moistened charge will burn cleaner, expand more uniformly, and in time result in the elimination of carbon deposits from the cylinders. The eduction of vapors from the crank-case, by returning to the cylinders the combustible gases which escape past the pistons, eliminates the loss of fuel values from this source, and also prevents dilution and lowered efficiency of the lubricating oil in the crank-case by the condensation therein of the gasoline vapors which leak past the pistons, or by liquid gasoline which may be drawn into the cylinders and eventually reach the crank-case without having been vaporized.

I am well aware that various devices have been heretofore proposed for withdrawing vapors from the crank-case and returning the same as a constituent of the charge supplied to the cylinders of an internal-combustion engine, and for utilizing moisture from the radiator as a further constituent of the charge, and my invention does not reside broadly in the provision of such devices, but in the combination and arrangement of the means for regulating and automatically controlling the same during the operation of the engine, and for facilitating the installation of the mechanism upon engines of the various designs employed in motor vehicles.

Referring again to the automatic suction-controlling valves, it is noted that the restrictive action of said valves, effective for a given suction in the manifold, is altered by varying the proportionate area of the valve-disks and of the stems which are subject to atmospheric pressure. Thus, if the diameter of the stem 43 be increased without correspondingly increasing the area of the disk 45, the restrictive action of the valve will be greater for a given suction, because a greater pressure-differential be-

tween the upper and lower sides of the disk is required to balance the atmospheric pressure upon the upper end of the stem.

Now, having described my invention, what I claim and desire to secure by Letters Patent is:

1. Auxiliary charge-forming means for liquid-cooled internal-combustion engines, comprising a conduit arranged to receive air and vapors from the cooling-fluid of the engine, a second conduit arranged to receive vapors from the crank-case of the engine, an adjusting-valve for each conduit to limit flow through the same, means connecting said conduits and arranged to deliver the vapors received therefrom to the intake manifold of the engine, and automatic suction-controlling means for each conduit, said suction-controlling means adapted and arranged to proportionally impede flow through the respective conduit as suction from the manifold is increased.

2. Auxiliary charge-forming means for internal-combustion engines, comprising a vapor-combining and controlling unit having two inlet passages and a common outlet passage, the latter being connected with the suction intake of the engine, an adjusting-valve for each inlet passage, there being a valve-chamber mediate each inlet passage and the common outlet, and an automatic control-valve arranged in each of said chambers and movable to variably impede flow thereto from the respective inlet passage, said valve being openable by pressure from the inlet passage and having a member constantly subject to atmospheric pressure tending to close the same, whereby during operation the valve is balanced at intermediate positions for maintaining a substantially constant pressure-differential between the respective inlet passage and the common outlet.

3. In a device of the class described, a suction-controlling valve comprising a body having a tapering valve-chamber communicating with an outlet near the larger end thereof and with an intake-passage at the smaller end thereof, a valve-seat formed at the end of said chamber adjoining the intake-passage, a valve engageable with said seat and movable into the larger portion of the chamber to variably impede flow of vapors from the intake-passage to the outlet, adjusting means for restricting the intake-passage, and biasing means tending to move said valve toward the seat when pressure in the intake-passage is less than atmospheric.

ADOLPH J. P. BERTSCHY.
